United States Patent Office

Des. 176,632
Patented Jan. 10, 1956

176,632

GAME DIE OR SIMILAR ARTICLE

Monroe H. Rosenow, Brookfield, Wis.

Application March 11, 1955, Serial No. 34,993

Term of patent 14 years

(Cl. D34—5)

Fig. 1.

Fig. 2.

Fig. 3.

Figure 1 is a perspective view showing three sides of a game die or similar article embodying my new design;

Figure 2 is a perspective view of the remaining three sides thereof; and

The dominant features of my new design are shown in solid lines on the drawing.

I claim:

The ornamental design for a game die or similar article, as shown and described.
